(57) **CLAIM**

I claim the ornamental design for an ice skate blade holder, as shown and described.

DESCRIPTION

FIG. 1 is a front side perspective view of an ice skate blade holder according to the present design;

FIG. 2 is a rear side perspective view thereof;

FIG. 3 is a left side elevational view thereof;

FIG. 4 is a right side elevational view thereof;

FIG. 5 is front elevational view thereof; and,

FIG. 6 is a rear elevational view thereof.

The broken lines are included for the purpose of illustrating environment and form no part of the claimed design.
